BY *James J. Morris*,
ATTORNEY.

UNITED STATES PATENT OFFICE

LE ROY W. WILLIS, OF BROOKLYN, NEW YORK, ASSIGNOR TO INTERTYPE CORPORATION, OF BROOKLYN, NEW YORK, A CORPORATION OF NEW YORK

ATTACHMENT FOR BREAKING TYPE SLUGS

Application filed June 18, 1929. Serial No. 371,924.

The present invention relates to improvement in means adapted for use in the production or preparation of type or type bars of short height for use in printing machines 5 of the class having a cylinder or plate provided with grooves into which such type bars are inserted and in which they are retained by the engagement of ribs on the longitudinal edges of the grooves in grooves in the type 10 bars, type or type bars of this general class being disclosed in United States Letters Patents No. 836,026, granted on November 13, 1906, to Harry C. Gammeter, No. 1,122,819 granted December 29, 1914 to George T. 15 Trundle, and No. 1,679,261 granted on July 31, 1928, to Joseph C. Norwood.

In the production of type bars of this class in the manner disclosed in the Trundle and Norwood patents above referred to, the type 20 bars are first cast as type high slugs in suitable type slug casting molds, the type face being carried on an edge of a portion of the slug which is to become the type bar, and such portion of the slug being connected to a gate 25 which is cast initially as a part of the slug by a thin or constricted neck portion which must be broken to detach the gate portion of the slug from the type bearing portion before the latter is in condition for insertion into 30 the printing machine.

The present invention provides means adapted to be mounted on or adjacent to the printing machine and constructed to receive the type high slug in the form in which it is 35 initially cast in the mold and to hold such slug, by engagement with the type bearing portion thereof, so that the gate portion of the slug projects into a position where it may be manually bent or swung relatively to the 40 type bearing portion to break the slug along the thin neck which connects the type bearing portion to the gate portion of the slug, thereby detaching the gate portion and thus preparing the type bearing portion for insertion into the printing machine. By 45 mounting the slug breaking means on the printing machine so that the portion of said means which receives the type bearing portion of the slug is aligned with the type receiving groove of the printing machine, the

type bearing portion of the slug will be in position to enter the printing machine immediately upon detachment of the gate portion of the slug therefrom.

To these and other things, the invention 55 consists in certain improvements and combinations and arrangements of parts, all of which will be hereinafter more fully described, the features of novelty being pointed out particularly in the claims at the end of 60 this specification.

In the accompanying drawings:—

Figure 1 is a perspective view of a slug 65 breaking device constructed in accordance with the preferred embodiment of the invention;

Figure 2 represents a transverse section through the device shown in Fig. 1, showing a type high slug inserted therein and indicating by the dotted lines the manner in which 70 the gate portion of the slug is broken or detached from the type bearing portion thereof; and

Figure 3 is a perspective view of a printing machine having the slug breaking device 75 mounted thereon so that the grooved cylinder of the printing machine will receive type bars from the slug breaking device.

Similar parts are designated by the same reference characters in the said views. 80

The slug breaking device in its preferred form comprises a frame 1 which may be formed of cast metal, this frame forming a pair of parallel longitudinal side members 2 which are connected at one end by a cross member 3 which may be formed integrally or as a part of the frame, and the side members 2 are connected at their opposite ends by a transverse portion 4 of the frame. Between the side members 2 of the frame are inserted a pair of jaws 5 which may be secured to the respective side members of the frame by screws 6, the jaws 5 being formed along their inner or proximate edges with grooves or under-cut portions 7, and the lower faces 8 of the jaws sloping away from the bottom walls 9 of the respective grooves, forming relatively sharp edges 10 at the junctions of the surfaces 8 with the bottom surfaces 9 of the grooves. 95 100

The jaws are adapted to receive the type bearing portion 11 of a type slug between their inner or proximate edges by insertion of the type slug longitudinally of the jaws, 5 the inner or adjacent edges of the jaws being preferably bevelled at the entrance or slug receiving end as indicated at 12 to facilitate the insertion of the slug. The sides of the type bearing portion 11 of the slug are 10 formed with grooves 13 into which the sharp edges of the jaws 5 fit, and the bottom of the type bearing portion 11 of the slug fits against the bottoms 9 of the grooves formed in the jaws, so that the type bearing portion 15 of the slug, when inserted between the jaws, will be substantially held against rocking or tilting motion about the longitudinal axis of the slug.

The type slug is initially cast in a mold of 20 a kind similar to that used in the casting of ordinary type high slugs or type bars used in printing, as, for example, as shown in the Trundle patent hereinabove referred to, the casting of these slugs in line casting machines 25 of the ordinary or well known class facilitating their production. In casting the slugs in that manner, the slug is formed initially with a gate 14 which is joined to the type bearing portion 11 by a relatively thin or constricted neck portion 15, and the gate portion of the 30 slug must be detached or removed from the type bearing portion thereof before the latter portion of the slug can be used in a printing machine of the class having grooves to receive 35 type bars of short height.

According to the present invention, the slugs are inserted into the slug breaking device so that the type bearing portion 11 thereof is received between the jaws in the 40 manner hereinbefore described, the gate portion 14 on the slug then projecting freely beneath the jaws, and by twisting or swinging the gate portion of the slug transversely or into one of the dotted line positions shown 45 in Fig. 2 while the type bearing portion of the slug is confined or held by the jaws, the relatively thin neck portion 15 of the slug which is engaged by the relatively sharp edges 14 of the jaws will be broken, the gate 50 being thus detached from the type bearing portion of the slug and the latter is then in condition for insertion into one of the type receiving grooves of a printing machine.

The slug breaking device embodying the 55 present invention may be mounted adjacent to the printing machine so that type bars, after the slug gates have been detached therefrom, may be conveniently inserted in the printing machine, but it is generally preferred to mount the slug breaking device on the printing machine so that the placing of the slug in the device will aline the type bearing portion of the slug with the type bar receiving slot in the printing machine, so 60 that the type bar can be inserted by sliding 65

into the printing machine immediately after the slug gate has been detached. Figure 3 shows the slug breaking device so mounted on the printing machine. In the instance shown, the frame of the slug breaking device 70 is formed with an extension 16 which is adapted to abut against the outer side of one of the end members 17 of the printing machine, this extension having a lug 18 thereon which is adapted to fit over the adjacent end 75 of the usual tie bar 19 which connects the end members of the printing machine, and a screw 20 may be passed through the lug 18 and the adjacent end of the tie bar 19 and threaded into the end member of the printing machine and tightened so that the lug 18 is drawn down solidly upon the top of the usual tie bar, thus securing the slug breaking device to the end member of the printing machine. A set screw 21 is preferably 80 threaded through another lug 22 formed on the extension 16 of the frame of the slug breaking device, this set screw being adapted to rest upon the top of the end member 17 of the printing machine, adjustment of the screw 21 serving to position the jaws 5 of the slug breaking device vertically with respect to the printing machine and thereby 85 enabling the slug engaging portions of these jaws to be alined with the type bar receiving slot 23 in the adjacent end member of the printing machine. A lock nut 24 threaded on the screw 21 serves to secure the screw in proper adjustment.

When the slug breaking device is thus secured to the printing machine it is supported firmly in a manner which enables pressure to be applied conveniently to the gate of the slug to detach it from the type bearing portion thereof, and since the jaws aline 105 the latter portion of the slug with the type bar receiving slot in the printing machine, the type bearing portion of the slug may be inserted into the printing machine immediately after detachment of the gate portion of the slug.

The slug breaking device is applicable generally to any printing machine of the class using short height type bars, the printing machine shown in the present instance 110 being of a well known class employing a cylinder 25, the periphery of which is formed with a series of circumferentially spaced grooves 26 to receive the type bars by a movement longitudinally through the slot 23 and into each groove when the latter is in register with the slot 23, the outer longitudinal edges of each groove in the printing machine being formed with in-turned ribs or ledges 27 to engage in the grooves 13 in the opposite sides 115 of the type bar and thereby retain the latter in the cylinder.

By holding the slug by the engagement of its type bearing portion 11 between the grooved edges of the jaws 5 while the narrow 120

or thin neck portion 15 which joins this portion of the slug with the gate portion thereof between the relatively sharp opposed edges 10 of the jaws, that portion of the slug can be broken and thus detached from the type bearing portion 11 without damaging in any way the type bearing portion of the slug, this mode of detaching the gate portion from the type bearing portion of the slug being 10 superior to that heretofore employed which consisted in pressing the type bearing portion of the slug against the surface of a table at an angle and with sufficient force to break the gate from the type bearing portion, since 15 such a procedure tends to bend or bow the relatively weak type bearing portion so that it does not freely enter the groove of the printing machine cylinder, and such method as heretofore used often results in damaging 20 the type characters and consequent imperfections in the printed impressions produced therefrom.

I claim as my invention:—

1. A device for detaching the gate from the oppositely-grooved type-bearing portion of a type slug, comprising opposed relatively fixed jaws spaced to receive the type-bearing portion of such slug and shaped to fit into the grooves therein and to expose the 25 gate of the slug for angular displacement relatively to the type-bearing portion thereof.

2. A device for detaching the gate from the oppositely-grooved type-bearing portion of a type slug, comprising opposed parallel relatively fixed jaws spaced transversely and having an entrance at one end to receive the oppositely-grooved type-bearing portion of the slug by longitudinal movement of the 35 slug relatively to said jaws and exposing the gate of the slug exteriorly of said jaws for angular displacement relatively to the type-bearing portion of the slug.

3. A device for detaching the gate from the oppositely-grooved type-bearing portion of a type slug, comprising opposed relatively fixed jaws having portions of their opposed faces shaped to fit the oppositely-grooved type-bearing portion of the slug and having opposed relatively fixed sharp edges to engage the junction of the type-bearing portion with the gate of the slug.

4. A device for detaching the gate from the oppositely-grooved type-bearing portion of a type slug, comprising opposed relatively fixed jaws spaced and shaped to receive the oppositely-grooved type-bearing portion between them and to expose the gate of the slug exteriorly thereof for angular displacement relatively to the type-bearing portion of the slug, the space between said jaws being formed with an enlarged tapered opening at one end to receive an end of the slug, 65 and the type-bearing portion being slid able

longitudinally between said relatively fixed jaws.

5. A device for detaching the gate from the type-bearing portion of a type slug wherein the latter portion of the slug is 70 grooved at its opposite sides and is connected to the gate thereof by a neck of less thickness than the gate, comprising a pair of opposed relatively fixed jaws having portions to fit into the grooves in the body portion of the slug and relatively fixed sharp edges to confine the relatively thin neck of the slug, the surfaces of the jaws adjacent to said edges being cut away to expose the gate portion of the slug for manual deflection with 75 respect to the type-bearing portion while the latter is held by said fixed jaws and the neck of the slug is confined between said fixed sharp edges.

6. The combination with a printing machine having grooves to receive type bars and a type-bar receiving slot with which said grooves are adapted to register, of a type slug breaking device secured to said machine and having jaws spaced apart to receive the type-bearing portion of a type slug and to aline such portion of the slug with 80 said receiving slot of the machine, said jaws exposing the gate portion of the slug for angular movement relatively to the type- 85 bearing portion to detach it therefrom.

7. The combination with a printing machine having grooves to receive type bars and a type-bar receiving slot with which said grooves are adapted to register, of a type slug breaking device having means for securing it to said machine and having jaws spaced apart to receive the type-bearing portion of a type slug, and to expose a gate portion of the slug for manual detachment from 90 the type-bearing portion, and means for adjusting said device relatively to the machine to aline the jaws with the receiving slot of the machine, the type-bearing portion of the slug, when the gate is detached therefrom, 95 being movable longitudinally between the jaws and into the receiving slot in the printing machine.

In testimony whereof I have hereunto set my hand.

LE ROY W. WILLIS.
